UNITED STATES PATENT OFFICE

2,505,921

ROTARY FOOD SLICING MACHINE

Albert Sporket, Detroit, Mich.

Application July 24, 1948, Serial No. 40,552

3 Claims. (Cl. 146—121)

1

This invention relates to slicing machines and, in particular, to food slicing machines.

One object of this invention is to provide a food slicing machine having a central replaceable hub or disc mounting for the cutting blade, preferably flanged, for which a similar part may be substituted in the event of wear.

Another object of this invention is to provide a food slicing machine, of the foregoing type, having a resilient concave tension disc which engages the peripheral portion of the cutter disc support and thereby reduces any tendency of the cutter disc to wobble and absorbs variations in manufacture or irregularities resulting from wear during use.

A still further object is to provide a food slicing machine having a dished or hollow-ground cutter disc, preferably saw-toothed, which causes the already cut portions of the food to spread apart after passing the cutting edge of the disc, thus greatly reducing friction between the food and the sides of the disc and eliminating the need for any "set" in the teeth.

In the drawings:

Figure 1 is a side elevation of a food slicing machine according to a preferred form of the invention;

Figure 2 is a top plan view of the food slicing machine shown in Figure 1;

Figure 3 is a vertical section taken along the line 3—3 in Figure 1; and

Figure 4 is a vertical section taken along the line 4—4 in Figure 1.

Referring to the drawings in detail, Figures 1 and 2 show a food slicer, generally designated 10, according to the invention. The machine 10 preferably embodies a base 11 to which is affixed a combination guard and support 12 by means of fasteners 13. Included in the guard and support 12 is a guard flange 14. Also integral with part 12 is a boss 15 containing a bore 15a in which a shaft 16 is rotatably mounted. Mounted on one end of the shaft 16 is a crank 17 mounted by means of a fastener 18. Mounted on the other end of shaft 16 is a pinion 19 meshing with a gear 20. The gear 20 has a central bore 20a by which it is rotatably mounted upon a flanged bearing member 21, which forms a stationary hub, also containing a central threaded bore to receive a fastener 22, preferably a threaded screw.

The fastener 22 (Figure 3) serves to secure the bearing member 21 to a second boss 23 integral with the guard and support 12 and extending inward. The boss 23 also contains a central bore to admit a fastener 22 which is common to parts 21

2

and 23. Separating hub 21 from boss 23 is a resilient concave tension disc 24, the purpose of which is to provide pressure to force gear 20 against flange 25 of the hub or bearing member 21, thus preventing it from wobbling. Extending through parts 21, 23 and 24 is a second bore containing an aligning pin 26, the purpose of which is to maintain the aforementioned three parts in a constant position relative to one another. Attached to the face of gear 20 by means of fasteners 27, is cutter disc 28, hollowed out or dished in such a fashion that its edges, preferably toothed, extend outward and forward. Within the base 11 of the device is an aperture 29 to admit the lower edge of cutter disc 28, thus permitting it to turn freely, unobstructed by base 11. Surrounding the upper end of this aperture 29 is a countersunk metal strip 30 secured to base 11 by fasteners 31.

The food slicing machine 10 includes an adjustable stop or gauging device (Figure 4) generally designated 32, for determining the thickness of the food to be cut. This features a vertical plate 33 on a plane parallel to that of the cutter disc. Attached to, or integral with, this plate 33 are a threaded bar 34 and a slide bar 35; both parallel bars pass through apertures in parallel supporting members 36 attached to base 11 by fasteners 37. Thus, the vertical plate 33, which comes into direct contact with the food, can be moved toward or away from the plane of the cutter disc. Adjustment of position of this part can be made by means of a rotatably threaded wheel nut 38, preferably knurled, mounted between supports 36 upon, and engaging with, the threaded bar 34. The purpose of slide bar 35 is to guide plate 33 and to prevent it from rotating around the axis of bar 34. Extending between supports 36 are two spacing members 39.

In the operation of the machine of this invention, the wheel nut 38 is rotated to adjust the stop or gauging device 32 to the position producing the desired thickness of the food slice. The food is then placed upon the base 11 against plate 33 and moved toward cutter disc 28, crank 17 being turned at the same time to rotate the disc.

What I claim is:

1. A slicing machine comprising a base, a frame structure mounted on said base and including a stationary hub projecting forwardly from said frame structure and having a retaining flange on the forward end thereof, a rotary cutter support rotatably mounted on said hub in engagement with said flange, a rotary cutter connected to said support, mechanism for rotating said cutter, and an axially yieldable spring member

mounted on said structure and engageable with the peripheral portions of said cutter support for urging said cutter support forwardly against said flange, said spring member having its central portion interposed between said hub and said frame structure and clamped therebetween.

2. A slicing machine comprising a base, a frame structure mounted on said base and including a stationary hub projecting forwardly from said frame structure and having a retaining flange on the forward end thereof, a rotary cutter support rotatably mounted on said hub in engagement with said flange, a rotary cutter connected to said support, mechanism for rotating said cutter, and an axially yieldable spring member mounted on said structure and engageable with said cutter support for urging said cutter support forwardly against said flange, said spring member engaging the peripheral portion of said cutter support.

3. A slicing machine comprising a base, a frame structure mounted on said base and including a stationary hub projecting forwardly from said frame structure and having a retaining flange on the forward end thereof, a gear 25

5 rotatably mounted on said hub and engageable with said flange, a rotary cutter connected to said gear, mechanism for rotating said cutter, and an axially yieldable spring member mounted on said structure and engageable with the peripheral portion of said gear forwardly for urging said gear against said flange.

ALBERT SPORKET.
